United States Patent Office

Des. 196,672
Patented Oct. 22, 1963

196,672

INDICATING INSTRUMENT

Wallace A. Monson, Golden Valley, Minn., assignor to
Minneapolis-Honeywell Regulator Company, Minne-
apolis, Minn., a corporation of Delaware

Filed Sept. 28, 1962, Ser. No. 71,913

Term of patent 14 years

(Cl. D52—6)

FIGURE 1 is a perspective view of an indicating instrument, showing my new design;

FIGURE 2 is a front view thereof.

FIGURE 3 is a left side view thereof.

FIGURE 4 is a bottom view thereof.

FIGURE 5 is a rear view thereof.

The essential features of the disclosed design reside in the portions shown in full lines.

I claim:

The ornamental design for an indicating instrument, as shown and described.
